UNITED STATES PATENT OFFICE.

ALBERT F. ROCKWELL AND VICTOR W. PAGE, OF BRISTOL, CONNECTICUT, ASSIGNEES
TO THE NEW DEPARTURE MANUFACTURING COMPANY, OF BRISTOL, CONNECTICUT,
A CORPORATION OF CONNECTICUT.

BELL.

1,237,818.

Specification of Letters Patent. Patented Aug. 21, 1917.

Application filed October 27, 1911. Serial No. 657,063.

To all whom it may concern:

Be it known that we, ALBERT F. ROCKWELL and VICTOR W. PAGE, citizens of the United States, residing at Bristol, county of 5 Hartford, State of Connecticut, have invented a certain new and useful Bell, of which the following is a full, clear, and exact description, such as will enable others skilled in the art to which it appertains to 10 make and use the same, reference being had to the accompanying drawings, forming part of this specification.

One object of our invention is to provide a bell so constructed and operated that 15 the operator may readily control the same.

A further object is to provide a plurality of means for operating a bell either interchangeably or simultaneously.

A further object is to provide means for 20 accelerating the speed of the moving member of said bell without stopping said moving member.

To these ends and also to improve generally upon devices of the character indicated, our invention consists in the various 25 matters hereinafter described and claimed.

In the accompanying drawings:

Figure 1 is a lateral view of our device, partially in section;

Fig. 2 is a front view in cross-section;

Fig. 3 is a side view of one clutch member;

Fig. 4 is a lateral view of our segment;

Fig. 5 is a front view, in cross section, of 35 our driving sleeve;

Fig. 6 is a front view, in cross-section, of our driving clutch member;

Fig. 7 is a lateral view, in cross-section, of our striking member; and

Fig. 8 is a modification, in cross-section.

Referring to the drawings as the illustrated embodiment of the invention, the device is adapted to be located preferably on the side of a vehicle near the seat in a position where it can be easily operated by the driver. A frame —1— is adapted to be secured positively to the side of the vehicle, and positively secured to said frame and extending laterally therefrom, is a stationary axle —2— upon which the movable members of the bell preferably rotate. One convenient and preferable means for driv-

ing said rotatable bell members is as follows. A handle —3—, for operating the bell, is positively secured to a segment 55 —4— which in turn is pivoted as at —5— to a stud extending laterally from said frame —1—. The segment preferably extends approximately 120° and has a rack —6— thereon engaging, and adapted to 60 drive, an intermediate gearing —27— and thereby a driving sleeve —7— which is mounted on the axle —2—. On the surface of the driving sleeve is provided a worm —8— which engages a complementary worm 65 recess in a driving clutch member —9—. It will be seen that, as the driving sleeve —7— is propelled, the worm, due to the tendency of the driving clutch member 70 9 to lag behind the clutch sleeve 7 on account of the member's inertia, tends to screw out of the grooves of the driving clutch member and thereby causes the driving clutch member —9— to have a lateral motion, and its diagonal clutch surface, as 75 at —10—, when moved laterally, frictionally engages a corresponding diagonal clutch surface —110— on a bell sleeve —11—, so that when the diagonal surfaces meet, both the bell sleeve —11—, the driving clutch 80 member —9—, and the driving sleeve —7— are operated by the movement of the segment so that they all revolve together about the axle —2—.

The bell is preferably divided into two 85 members, the inner member —12— and the outer member —13—, both of which are preferably, positively secured to said bell-sleeve —11—, all of said parts being preferably mounted on ball bearings 34 and 35 90 (Fig. 2), and being held in proper location by a lock-nut —14— on the end of said axle —2— and acting to force the outer race member of the bearing 35 against the shoulder 36 of the bell sleeve 11. In this 95 way the bell is given a demountable structure as the bearing is detachably carried upon the spindle 2 and the sleeve is detachably carried upon both bearings. The bell and the bell sleeve —11— may be secured 100 together in any suitable manner and, for convenience of manufacture, it is preferred to have them separate but movable together and they may be termed a movable member.

In the operation of our bell, as soon as the segment —4— has reached the end of its stroke, or for any reason the segment and its handle —3— are stopped, the momentum of the bell and the bell sleeve —11— will continue both rotating as one movable member, and, in that the driving clutch member —9— is at that moment engaged with the clutch surface of the bell sleeve, the sleeve will rotate the member and, due to the threads, will give it a lateral movement away from the sleeve until contact at 110 is broken, thus releasing the clutch members as soon as the driving sleeve —7— stops rotating or has less speed than the bell itself. Consequently, as soon as the clutch is released, the bell members continue to rotate free from the driving clutch member —9—, until the operator desires again to drive the bell by means of the handle —3— as described.

It is preferred to have it possible for the bell members to continue to rotate and be continually propelled, if necessary, by another means and, if desired, either interchangeably or simultaneously with the above said driving means.

The other convenient and preferable means of rotating said bell, which preferably rotates the bell somewhat slower than the above said driving means, is as follows. Preferably, at the lower end of the frame —1—, is provided an extension —15— which has a bushing therein, as at —16— adapted to carry a shaft —17—. This shaft —17— may be operated in any suitable manner, such as by being engaged with a flexible shaft —17^a— which can be operated by any suitable means in the vehicle. At the opposite end of the shaft —17— we provide a pinion —18— which in turn engages teeth in a ring —19— positively secured, as at —20—, to the bell sleeve —11—, and thereby the bell member may be rotated continually, or as desired, by means of the said shaft —17—. Of course, this means of operating the shaft —17— may be in continual operation or in temporary operation, as the driver desires, preferably being controlled by any suitable means in engagement therewith.

If the speed of the bell sleeve —11— is to be accelerated by means such for example as that first described above, to a speed greater than that given it by means of the shaft —17—, we provide an automatic clutch member —28—, Fig. 3, preferably located at the end of the shaft —17—, between said shaft and its driving means, so that, when the clutch —28— is released, the driving means, such as a flexible shaft —17^a—, though attached thereto, may have less speed than the shaft —17—, which is in continual engagement with the movable members of our bell. On the other hand, if the

speed of the shaft —17— becomes less than that of the flexible shaft —17^a—, the clutch —28— will automatically take hold and drive the shaft —17—. As a preferable form of construction, our clutch —28— has an inner member —29— secured to our flexible shaft —17^a— and an outer member —30— secured to our shaft —17—. The outer member —30— has preferably a plurality of eccentric surfaces up which surfaces movable members, such as balls —31—, ride to frictionally engage both the inner and outer members when the inner member moves comparatively in one direction. When the inner member is moved comparatively in the opposite direction the balls —31— are released and the inner and outer members move free from each other.

Consequently, it will be seen that we provide two means of propelling our bell members which may operate simultaneously or separately at the convenience of the driver of the vehicle.

The sounding mechanism of the bell is as follows: On our inner bell member —12—, preferably integral therewith, we provide a lug —21—, and on our outer bell member —13—, we provide a similar lug —22—. These lugs are preferably arranged at opposite sides of the bell itself and are adapted to be struck a blow alternately by hammers —25— and —26— on a striking arm —23— to sound the bell or gong. This striking arm —23— is preferably pivoted to said bell sleeve —11— by means of a bearing —24— and is adapted to hang by gravity preferably within the lower part of the bell with the hammers in the path of the lugs on the bell members. The bell members are adapted to rotate so that the lugs —21— and —22—, as they revolve, alternately meet the striker to sound the bell. On the lower end of our striker —23—, we preferably arrange a transverse bolt —24^a— which carries the hammers —25—, —26— loosely mounted thereon, so that they slide radially back and forth toward the center of the bell as they meet the lugs —21— and —22— when the bell rotates, whereby a clear, loud, distinct tone is thereby given to the bell without impeding the movement of the same, when the bell members are driven by either of the above referred to driving means.

As a modified embodiment of our invention, in Fig. 8, the bell members —12^a— and —13^a— are preferably stationary while striking arms —23^a— are preferably adapted to revolve therein to deliver blows on the lugs —21^a— and —22^a—. The striking arms —23^a— extend from and are preferably integral with a ring —32— on one side of which there is an inner flange —33—. On the opposite side the ring is preferably threaded to an external flange —11^a— on the

sleeve —11^b— and is thereby detachably mounted in place on the bearing —24^b— abutting the shoulder —2^a— on the shaft —2—, the striking members thus being secured to the sleeve —11^b— to revolve therewith on the said bearing —24^b—.

The bell member —13^a— is spaced from the bearing —24^b— by the sleeve —37— and the parts are held assembled upon the axle —2— by the nut —38—. The bearing —24^b— is shown as of the "unit-handling" type *i. e.*, it, by virtue of its own construction, remains assembled so that its race members and antifriction members will not separate and fall apart. We prefer this type of bearing as, with it, no means, other than the bearing itself, is needed to keep the arm —23^a— and the ring —32— mounted upon the axle.

20 In the modified form of Fig. 8 we may, as illustrated, use the frame 1, axle 2, handle 3, segment 4, pivot 5 and rack 6 practically as in Fig. 2 but in this modified form we use a shaft 27^a operatively connected with 25 the rack 6 and such shaft, by means of the gear 27^b, drives the driving sleeve 7^a, the sleeve 7^a, by its worm 8^a, being connected with the laterally shiftable taper-clutch element 9^a adapted to engage the taper-clutch 30 surface of the sleeve 11^b at 10^a. Thus, with this structure, the arms 23^a are caused to rotate to bring the hammers 25^a and 26^a into contact with the strike-lugs of the gongs.

Having thus described our invention, what 35 we claim as new and desire to secure by Letters Patent is—

1. In combination in a bell, a movable sounding member and a plurality of means for driving said movable member, each of 40 which means is automatically releasable from said movable member when its driving tendency is exceeded by that of the other; substantially as described.

2. In combination in a bell, a movable sounding member and a plurality of means for driving said movable member, each of 45 which means is automatically releasable from said movable member when the speed produced thereby is less than the speed of said movable member; substantially as described.

3. In combination in a bell, a movable sounding member and a plurality of means for driving said movable member, each of 50 which will operate said movable member only when it can accelerate the speed of said movable member; substantially as described.

4. In combination in a bell, a gong providing member and a gong-sounding member, one of said members being movable with respect to the other thereby to meet such other member to sound the bell, said movable member comprising a sleeve having a portion for mounting upon a bearing and 65 a portion for engagement with a driving

clutch member, a support, a thrust bearing carried by said support, said sleeve being connected with said bearing and holding said movable member in place thereon, a driving clutch member to be thrust against 70 said clutch-member-engaging portion to establish a driving connection therewith, and means for exerting thrust upon said clutch member; substantially as described.

5. In a bell, a member adapted for continuous rotation, a driving means therefor, a second driving means therefor, means for operatively connecting one of said means with said member, and means for operatively connecting the other of said driving means 80 with said member while the latter is moving without checking the movement of said member previously derived from the one said driving means; substantially as described.

6. In a bell, a member adapted for continuous rotation, a low-speed driving means therefor, a high-speed driving means therefor, means for operatively connecting one of said means with said member, and means 90 for operatively connecting the other of said driving means with said member while the latter is moving without checking the movement of said member previously derived from the one said driving means; substantially as described.

7. In a bell, a member to be set into vibration to produce sound and a member to cause such vibration, one of said members being movable to meet the other to sound the bell, 100 a driving means for driving said movable member, and means for operatively connecting said driving means and said movable member to drive such member and for totally disconnecting said driving means from 105 such member whenever said driving means is stopped or retarded with respect to such member thereby to permit such member to continue its movement entirely unimpeded by said driving means; substantially as described.

8. In combination in a bell, a pair of members adapted to meet to sound the bell, one of said members being movable into meeting relation with the other, two distinct 115 driving means for driving said movable member, and means for connecting either of said driving means with said movable member to drive such member from either of said driving means wholly independent of and 120 in non-impeded relation to the non-acting driving means; substantially as described.

9. In combination in a bell, a movable hollow member, a sounding member carried by said hollow member for movement therewith and to be driven thereby, a striking means for said sounding member pivotally carried by said hollow member, and driving means received within said hollow member and located for driving connection therewith 125

thereby to drive said sounding member through said hollow member; substantially as described.

10. In a bell, a spindle, a hollow sleeve rotatably mounted thereon, a pair of gongs fixed to said sleeve and each having a strike lug, a striking means pivotally mounted upon said sleeve and extending into the path of movement of said lugs and means for driving said sleeve received within said sleeve; substantially as described.

11. In a bell, a spindle, a sleeve rotatably mounted thereon, a pair of dished gongs fixed to said sleeve with their edges closely adjacent, a striking means for said gongs pivotally carried by said sleeve and housed by said gongs, and means for driving said sleeve; substantially as described.

12. In a bell having a demountable structure, in combination, a gong providing member and a gong sounding member, one of said members being movable with respect to the other to thereby meet such other member and sound the bell, a support, a bearing carried by said support and carrying said movable member, such movable member having an aperture with an inwardly projecting abutment and said bearing being received in said aperture and abutting said

abutment, and detachable means for forcing said bearing against said abutment; substantially as described.

13. In a bell, in combination, a spindle, a sounding-member-carrying sleeve rotatably mounted upon and of greater diameter than said spindle; said sleeve being provided internally with a tapered clutch surface; an exteriorly threaded rotatable driving sleeve carried upon said spindle and within said carrying sleeve, an interiorly threaded exteriorly tapered driving clutch member rotatably engaged upon the threads of said driving sleeve and in operative relation with the clutch surface of said carrying sleeve, a sounding member carried by said carrying sleeve for rotation therewith and provided with a strike lug, and a striker member loosely carried upon said carrying sleeve and extending into the path of said lug; substantially as described.

In testimony whereof, we hereunto affix our signatures in the presence of two witnesses.

ALBERT F. ROCKWELL.
VICTOR W. PAGE.
